United States Patent Office

Des. 213,045
Patented Dec. 31, 1968

213,045

GOLF CART

Harold Saunders, 10759 W. 25th St., Lakewood,
Colo. 80215

Filed Jan. 26, 1968, Ser. No. 10,325

Term of patent 14 years

(Cl. D14—3)

FIG. 4

FIG. 5

FIG. 6

FIG. 7

FIGURE 1 is a perspective view of a golf cart showing my new design;

FIGURE 2 is a top plan view of the platform of the golf cart of FIGURE 1;

FIGURE 3 is a rear end elevational view of the platform shown in FIGURE 2;

FIGURE 4 is a bottom plan view of the platform shown in FIGURE 2;

FIGURE 5 is a left side elevational view of the platform shown in FIGURE 2;

FIGURE 6 is a right side elevational view of the platform shown in FIGURE 2; and

FIGURE 7 is a front end elevational view of the platform shown in FIGURE 2.

The dominant features of my new design are shown in solid lines.

I claim:

The ornamental design for a golf cart, as shown and described.
